DUAL AUTOMATIC INTERMITTING UNIT

Walter Brauer, Oklahoma City, Okla.

Application June 2, 1941, Serial No. 386,263

10 Claims. (Cl. 103—260)

This invention relates to the flowing of liquid from wells and more particularly, but not by way of limitation for separation of the liquifiable constituents from a liquid having a high gas-oil ratio, and to the automatic intermitting apparatus for controlling the emission of motive fluid pressure for raising the liquid out of the well. This application is a continuation in part of my co-pending application, Serial No. 378,284, filed February 10, 1941.

In the production of oil from wells having an unusually high gas-oil ratio, or in wells creating a large volume of gas, it has been found advantageous to allow the gas to expand in the annular space between the tubing and casing where the change in the pressure and temperature of the expanded gas effects a condensation of the liquifiable constituents present in the gas such as naphtha, gasolines, etc. The liquifiable constituents upon becoming condensed fall back into the lowermost portion of the well, which in conjunction with the liquid flowing from the oil bearing strata, forms a hydrostatic head of liquid capable of being lifted from the well.

In present day production of oil in most oil producing states the use of motive pressure gas for lifting or displacing oil from the well hole has given rise to the practicability of automatic intermitting systems. Heretofore fluid actuated pumps or gas controlled differential valves have given little consideration to the oil or sand pressure of the well in that motive fluid pressure for the lifting apparatus has been directed from the well surface and allowed to be forced against the well sand, thus having a tendency to oppose the normal lift of well liquid flowing from the formation. Furthermore, the use of mechanical devices such as springs, bellows and the like has given little consideration to the volume of liquid to be lifted relative to an efficient gas-oil ratio by utilizing the proper amount of gas for displacing a predetermined volume of oil.

It is therefore an important object of this invention to provide means for lifting liquids from a well which are so constructed and operated as to prevent placing a pressure on the well formation sand which would cause recession of the liquids desired to be lifted.

Another object of this invention is to provide an automatic intermitting device which will allow expansion of gases created by the sand pressure of the well to allow a condensation of the liquifiable constituents in the gases, and lifting the condensates through the medium of motive fluid pressure entering the eduction tubing in pre-

determined quantities responsive to changes in the condensate level standing in the well.

A further object of this invention is to provide an automatic intermitting apparatus for motive fluid lifting of liquid from a well which reduces the gas-oil ratio and provides a greater efficiency in the use of the motive fluid energy.

Another object of this invention is to intermittently gas lift oil from wells by introducing or jetting into the oil a motive fluid pressure and controlling the same automatically by a valve operated and controlled by a float cylinder responsive to the height of the liquid level standing in the well, said liquid level partially created by a condensation of liquifiable constituents from the well gas expanded in the well.

And still another object of this invention is to intermittently displace oil from a well by motive fluid pressure automatically injected by a valve which in turn is operated and controlled by a float cylinder responsive to the height of the liquid level to be lifted wherein the liquid acts as a stopper for a float cylinder actuating the valve to allow the input fluid to provide buoyant characteristics to the cylinder causing it to move vertically in actuation of the valve.

Other objects and advantages of the invention will be evident from the following detailed description read in conjunction with the accompanying drawings which illustrate one form of my invention.

In the drawings:

Fig. 1 is a fragmentary vertical sectional view of the uppermost sections of the tubing shown disposed in the well casing and having certain parts in elevation and showing the inlet means for the motive fluid.

Fig. 1—A is a view similar to Fig. 1 showing the disposition of the automatic intermitting unit.

Fig. 1—B is a similar view showing the disposition of the tubing catcher and the motive fluid outlet nozzle.

Fig. 1—C is a similar view showing the lowermost sections of the well tubing and the arrangement of the control and choke valves therein.

Fig. 2 is a vertical elevational view of the liquid lifting apparatus shown disposed in a well hole.

Fig. 3 is a view taken on lines 3—3 of Fig. 1—B.

Fig. 4 is a view taken on lines 4—4 of Fig. 1—A.

Fig. 5 is a view taken on lines 5—5 of Fig. 1—A.

Fig. 6 is an enlarged detailed sectional view of one of the check valves.

Referring to the drawings in detail and more particularly to Figs. 1 through 1—C inclusive, 55 reference character 2 designates a string of casing

suspended in an oil well hole. A string of tubing 4 is arranged in spaced relation to the casing 2 and extends through the length of the well. A string of smaller sized pipe or tubing 6 (preferably $\frac{1}{4}$ inch) is disposed in the space 8 between the tubing and the casing. A plurality of clamps 10 are vertically spaced along the string of tubing 4 for anchoring the smaller tubing 6 in the space 8. In the uppermost portion of the apparatus, tubing sections 4 are coupled together by a collar 12 having outwardly protruding or flanged portion 14 provided with a threaded aperture 16 for receiving an inlet check valve 18 of the ball type shown in detail in Fig. 6.

Below the coupling 12 the sections of tubing 4 are coupled by a collar 20 and an apertured nut 21 to which is threaded a valve cage 22 encircling a ball valve 24 cooperating with a seat 26 seated on the nut 21. The valve acts as a check against the inlet motive fluid or as an outlet valve for the lifted oil as will be hereinafter set forth.

Sections of tubing 4 extend into threaded engagement at 28 (Fig. 1—A) with a collar 30 substantially H-shaped (in cross section). Interposed in the tubing between the nut 21 and the collar 30 is an auxiliary valve unit A which will be hereinafter explained. The collar 30 is constructed to contain the automatic intermitting valve unit B which will be hereinafter referred to. The smaller tubing 6 extends through space 8 into communication with a longitudinal port 34 of the collar 30.

Sections of the tubing 4 extend below the collar 30 into threaded engagement with a collar 36 (Fig. 1—B) which in turn receives a nut 38. The smaller tubing 6 extends downward from a longitudinal port 40 in collar 30 into engagement with a longitudinal port 42 in collar 36, said port 42 in turn communicates with a radial port 44 in nut 38. A section of the tubing 4 is threaded at 46 to nut 38 and extends downwardly therefrom. The small pipe 6 communicates with port 44 by being disposed in a threaded bore 48 of nut 38, and from this point downward it is disposed in the interior of the tubing 4.

From Fig. 3 it will be noted that the nut 38 is constructed with substantially semi-circular apertures or ports 50 acting as outlet or upflow ports for the lifted liquid as will be hereinafter set forth. A baffle portion 51 prevents communication between the ports 44 and 50.

At a predetermined point below the nut 38 the tubing is provided with a tubing catcher 52 (Fig. 1—B), comprising an annular weighted member 54 having tapered upper side walls 56 cooperating with a pair of annular tapered slips 58 supported in inoperative position on an annular flange 60 of member 54. The member 54 is in turn supported on a helical spring 62 disposed around the tubing 4 and having its lower end anchored to a collar 64 fixed to the tubing 4. In running the tubing string in the well the slips 58 are spaced from and do not contact the inner periphery of the casing 2. However, when it is desired to set the tubing string in the well at a predetermined position in proximity of the oil bearing strata or shot hole, a reciprocation of the tubing causes a simultaneous contraction and expansion of the resilient spring 62 which effects an upward movement of the member 54 causing the slips to engage with the casing 2 and set the tubing string in the well.

It will be apparent that the lowermost end of

the small pipe 6 will be disposed at a point in the tubing 4 wherever it is desired to pneumatically displace a column of fluid standing in the tubing 4. A nozzle 66 is secured to the end of pipe 6 and is provided with a plurality of jets or apertures 68 (only one of which is shown). It is to be noted that the jet 68 is disposed in an upstream direction to assist the lifting and not direct motive fluid pressure downward against the oil flowing from the sand into the tubing 4. A valve unit is arranged in the tubing 4 below the nozzle 66 and is constructed similar to the valve 24 in the uppermost section of the tubing. The valve unit (Fig. 1—C) comprises a collar 70 connecting a section of the tubing 4 with a nut 72 to which is threaded valve cage 74 encircling ball valve 76 cooperating with seat 78. Tension is applied against the ball 76 by means of an adjustable unit 80 comprising a helical spring 82 anchored between the upper and lower plates 84 and 86 respectively. The lower plate contacts ball 76. Adjustability is provided by a threaded screw 88 arranged in the top of the cage 74 and contacting the upper plate 84.

A section of the tubing extends from nut 72 into connection with a collar 90 having diametrically opposed outward projections 92 provided with threaded apertures 94 for receiving valves 96 of the ball type. In the present instance two valves are preferably used; however, it will be understood that any number of apertures and valves may be utilized in the collar. The valves 96 act as inlet valves for the oil to be lifted and are identical in structure with the valves 18 in the uppermost sections of the tubing.

Referring to Fig. 6 showing a valve in detail, it comprises an externally threaded cylinder 98 formed with a small bore 100 communicating with a larger bore 102. A ball 104 is disposed in bore 102 and allows flow of motive fluid present in the casing through a valve 18 while both upper and lower valves act as a check for the liquid in the tubing by seating the ball against one end of the bore 100. A single rib or baffle 106 retains the ball in the bore 102. The tubing extends from collar 90 to a point in the well where it is closed off by a conventional bull plug 108 threaded in the lower end thereof.

Referring now to the automatic intermitting apparatus comprising units A and B, the apparatus is substantially identical with that disclosed in applicant's co-pending application heretofore mentioned, but in addition includes the auxiliary valve unit A for a purpose as will be hereinafter set forth.

The collar 30 (Fig. 1—A) has a central body portion 110 provided with a longitudinal bore 112. A cylindrical valve sleeve 114 is fitted (preferably by sweating) in the bore 112 and is maintained by a lock nut 116. The sleeve is adapted to receive a valve 118 comprising a freely movable shaft having a central bore 120 (shown in dotted lines) formed through its longitudinal axis. The lowermost end of the valve extends through the sleeve 114 into threaded engagement with the ball coupling joint 122. Although not shown in the present application, but clearly explained in the co-pending application, the lowermost portion of the bore 120 is of increased diameter for housing a small spring actuated check valve to check the inflow of gas as will be hereinafter explained. The collar 30 is provided with a radial bore or port 124 providing communication between the ports 34 and 40. The bore 124 communicates with diametrically opposed ports

126 provided centrally of the valve sleeve 114. The body of the valve 120 is reduced in diameter at 128 to allow passage of motive fluid from port 124 through the ports 126 and around the valve into the port 40 receiving the extension of small tubing 6. The bore 120 is in communication with port 124 through a small passageway 130 adapted when the valve is in lowermost position to communicate with an annular grooved portion 132 provided in valve 118, which in turn is provided with a small radial port (not shown). It will be understood that this construction allows communication between bore 120 and port 124 regardless of the angular position of the valve 118.

The lowermost portion of the valve has a stop collar 134 fixed thereto to limit the upstroke of the valve shaft in actual operation and to assure proper alignment of the inlet gas ports as will be hereinafter set forth. The ball joint or flexible unit 122 comprises a flanged nut 136 secured to the lower end of the valve shaft and having the flange connected to a cylindrical housing 138 in which is disposed an apertured member 140 having a semi-spherical projection 142 cooperating with complementary semi-spherical recess in the lower face of the nut 122. A spring 144 encircles the member 140 and urges it into contact with the nut 122. It will be understood that the nut 136 and member 140 are provided with aligned bores or apertures to provide communication of the inlet gas with a threaded sleeve 146 connecting the flexible union 122 with a cylindrical float member 148.

The auxiliary valve unit A shown above the intermitting unit B is disposed between collars 152 and 154 connecting sections of tubing 4. The valve comprises a collar 156 having a central longitudinal bore 158 in which is disposed a circular valve shaft 160. The lower end of the shaft is threadedly connected by nut 162 to the intermitting valve 118 and is adapted to move through the bore 158 in cooperation with the valve 118 as will be hereinafter set forth. The collar 156 is provided with a smaller longitudinal bore or port 164 baffled from bore 158 and extending upward into communication with a horizontally disposed bore 166 provided in the collar 156 which provides communication with bore 164 and a second longitudinal port 168 extending from port 166 to the top of the collar. A small bleeder port 167 (preferably $\frac{1}{16}$ of an inch) extends upward in the collar from port 164. The ports 167 and 168 communicate with threaded recesses 170 and 172 respectively, which in turn receive apertured choke members 174 and 176 respectively for a purpose as will be hereinafter set forth. The valve shaft 160 is provided with a reduced annular portion 178 for a purpose as will be hereinafter explained. The auxiliary unit A is preferably disposed six feet above unit B, but not limited thereto.

Referring to Fig. 4, it is to be noted that the collar 30 is provided with semi-circular ports 180 acting as outlets for the lifted fluid upwardly through the eduction string 4. These ports 180 are baffled off from port 124 by a central body portion 182.

Alluding to the float 148, it is preferably comprised of $\frac{1}{16}$ inch boiler sheet metal pipe and is approximately two inches in diameter by six feet in length, but not limited thereto. The lowermost portion of the float has longitudinal ribs 149 to keep it in proper alignment with respect to the inner periphery of the tubing 4. It will be apparent that the space 150 between the float 148

and tubing 4 is sufficient to allow passage of motive fluid past the float cylinder 148 without any upward lift thereof as will be hereinafter set forth. Furthermore, the ball coupling 122 assures free movement of the valve shaft 118 regardless of any possible distorted alignment of the float 148. The float is extremely light, but since the internal pressure of the float and that of space 144 are equal, there is no danger of crushing the float.

Operation

In wells producing a high gas-oil ratio, the gas, due to its lighter density, will flow from the oil and gas bearing strata much more rapidly into the well hole. Furthermore, in some instances the ratio of gas is such that the sand is discharging a much greater percentage of gas than oil. In this condition the present invention allows expansion of the discharging gas upwardly in the annular space 8 between the tubing and the casing throughout the complete length of the well hole, it being understood that there are no packers or baffle members in the well hole, the well being only packed off at the surface thereof. Upon expansion of the gas in the uppermost portions of the space 8 there is an increase in volume creating a change in pressure and temperature to cause a condensation of the liquifiable constituents contained in the gas, which, upon condensation, will fall back into the lowermost portions of the well hole and build up a hydrostatic head of liquid. In many wells the condensed liquifiable constituents of the gas substantially provide all of the column of fluid to be lifted; however, it will be understood that any liquid flowing from the sand cooperates with the condensates to provide a hydrostatic head of liquid. As the lighter liquids condense, gas remaining in the uppermost portions is directed through the slots or ports 7 of the tubing 6 for use as motive fluid for actuation of the lifting apparatus. It will be understood that the present invention is not limited to the use of gaseous pressure from the well as motive fluid, but may utilize extraneous motive fluid from the surface of the well in any conventional manner.

With a sufficient hydrostatic head of fluid built up in the space 8 such fluid is discharged through the check valve 96, ball valves 76, upwardly past nozzle 66, nut 38 until it reaches a level in the interior of the tubing substantially in proximity of the float cylinder 148. As long as the oil to be lifted is below the lowermost end of the float the valve 118 is in inoperative position in that the nut 162 is abutting the top face of cylindrical seat 114. In this position (not shown) the annular groove 132 is in alignment with the ports 130 allowing discharge of motive fluid from tubing 6, ports 34 and 124, into the longitudinal bore 120 of valve 118. This fluid is of sufficient pressure to unseat the small check valve (not shown) in bore 120 and flow into the interior of the float 148. The small dimension of the bore 120 does not allow for any large volume of gas to pass through the float into contact with the oil standing below. Consequently, there is no detrimental effect against the back pressure of the well lifting the oil. With the valve in this inoperative position motive fluid flowing into the float passes beneath the bottom end thereof and upward through the space 150, ports 180, bore 164, continuous bleeder 167 and choke 174 upwardly through the eduction tubing 4. It will be understood in this position the reduced portion 178 of valve shaft 160

is out of alignment with the horizontal port 166. The arrangement of the collar 156 and its co-operating valve shaft 160 is such that in inoperative position it precludes the possibility of liquid emitting upwardly through the tubing for any reason whatsoever until the column of liquid and the increased density of the gas flowing into the cylinder 148 causes the cylinder to float and provide a simultaneous operation of valves 118 and 160. The construction of the apparatus is such as to provide sufficient space for passage of this small amount of gas without any possibility of lifting the float 148 thus moving the valves 118 and 160 out of alignment with respect to ports 124 and 166 respectively.

With an increase of the hydrostatic head of liquid to a point above the bottom end of the float 148, the float not being buoyant will submerge into the oil. However, in this condition the liquid acts as a stopper or cork for the open end of the float so that the motive fluid emitting from bore 120 and directed into the interior of the float is prevented from passing around the bottom end thereof. In this condition the interior of the float provides a limited space or volume for the small amount of motive fluid discharging therein, and with the continued discharge from bore 120, it will be apparent that the density and pressure of the gas will increase sufficiently to give a buoyant effect to the cylinder 148 and cause it to float in the liquid pool, thereby moving it upwardly in a vertical path. Upward vertical movement of the cylinder 148 causes a simultaneous upward movement of the valves 118 and 160 to a point where the reduced portion 128 of valve 118 is in alignment with port 124, and reduced portion 178 of valve 160 is in alignment with port 166. The stop collar 134 limits the vertical upward travel of the valves to assure proper alignment.

In this operative position of the valve shafts, motive fluid is directed from tubing 6, port 124, around reduced portion 128 into ports 40, 42, the lowermost sections of tubing 6, to be jetted outwardly from the nozzle aperture 68. With the outward discharge of motive fluid pressure in an upstream direction into the column of liquid standing in the tubing, the liquid is lifted in the eduction tubing through ports 180, bores 164, 166, 168, apertured choke 176 through ball valve 24 on to the top of the well. The bore in choke 176 is smaller in diameter than port 168 and prevents any cutting action at the valve due to pressure. Motive fluid present in the uppermost sections of the well is allowed to flow through check valve 18 for boosting or assisting the lifting of the liquid column by the motive fluid emitting from nozzle 68. Furthermore, the pressure and speed of the motive fluid displaces the oil through the eduction tubing with such velocity as to substantially eliminate paraffin deposits in the tubing. It will be apparent that the float cylinder 148 will maintain the valves 118 and 160 in an upward or operative position as long as the cylinder 140 floats. The valve 118 is balanced since it is the same diameter on both sides of the main port 126. Furthermore, the collar 156 can be provided with horizontally disposed ports (not shown) arranged on both sides of port 166 in order to allow induction of outside gas pressure for balancing the valve 160 as well as keeping it clean of sand and other detrimental elements.

With the oil displaced in the tubing above the bottom end of float cylinder 148, the supply gas

contained therein escapes and the float cylinder moves the valves 118 and 160 downward to a position where the nut 162 abuts the top of the seat 114. In this position the motive fluid is then directed through bore 120 into cylinder 148 where it is discharged up through the eduction tubing until such time as the liquid level is raised to float the cylinder 148.

The valves 96 by a restricted opening act as a choke to provide the proper gas-oil ratio in the tubing, because, if such restriction were not present in wells having tremendous gas pressure, gas would be induced in the tubing 4 to continuously slug the oil upward regardless of any change in density of gas in the float cylinder 148 and the intermittent effect desired. The bleeder port 167 allows emission of gas up the tubing 4 to prevent a pressure condition within the cylinder 148 equal to that of space 8 thereby assuring intermittent action of the float cylinder. The adjustable valve unit 30 applies tension through spring 82 to assure that the pressure inside the tubing 4 is always less than that of the outside, thus preventing any balancing of pressures and assure that the motive fluid can flow into the float cylinder to assure the intermittent action.

From the foregoing it will be apparent that the automatic intermitting apparatus is arranged in the well hole in order to allow expansion of pressure gas from the well into the uppermost sections of the well thereby creating a condensation of the liquifiable constituents of the gas to provide a submergence level which acts as a stopper for the float cylinder thus making it capable of having buoyant characteristics by increasing the density of the input motive fluid therein and causing an upward movement of the cylinder for actuating the intermitting valve and its auxiliary choke valve to allow input motive fluid to be jetted into the liquid column below the float cylinder. Furthermore, the device precludes the possibility of continuous slugging of the oil in wells having tremendous gas pressures in that the auxiliary valve chokes off the flow of oil upward in the eduction tubing thus assuring an intermittent action in lifting the oil. The apparatus is automatic in its operation in that no extraneous time controlled mechanism is necessary, and the time interval for the intermittent operation of the automatic valve unit can be determined by known dimensions and the bottom hole pressure of the well. It will be apparent that the device is simple and efficient in its operation and assures an intermittent action for slugging the column of liquid under any well condition. The working parts are easily assembled and synergistic in their relations to one another.

Changes may be made in the combination and arrangement of parts as heretofore set forth in the specification and shown in the drawings, it being understood that any modification in the precise embodiment of the invention may be made within the scope of the following claims without departing from the spirit of the invention.

What I claim is:

1. In a pressure fluid lifting apparatus disposed in the eduction tubing of a well, a valve collar interposed in the tubing, a movable inlet valve arranged therein, open ended means movable to sink and float in the liquid being lifted, said means operably cooperating with the valve whereby floating of the means will move the

valve to flow inlet pressure fluid therethrough into the eduction tubing for displacing the liquid, and means precluding the flow of liquid from the well until flowing of pressure fluid through the inlet valve.

2. In a pressure fluid lifting apparatus disposed in the eduction tubing of a well, a movable inlet valve arranged in the tubing, a cylinder flexibly connected to said valve, means providing inlet fluid communication between the valve and the cylinder, said cylinder responsive to the liquid level in the well and the density of the pressure fluid in the cylinder to acquire buoyancy and move the valve whereby inlet fluid is passed therethrough into the eduction tubing for lifting the liquid, and means for precluding the flow of liquid from the well until the flowing of inlet fluid through the valve.

3. In a pressure fluid lifting apparatus disposed in the eduction tubing of a well, a movable inlet valve arranged in the tubing, operating means flexibly connected to the said valve, means providing inlet pressure communication between the valve and the operating means, said operating means responsive to the liquid level and the density of the pressure fluid in the operating means to provide buoyant characteristics to the operating means whereby the valve is moved to allow inlet pressure fluid to flow therethrough into the eduction tubing for displacing the liquid, and means for precluding the flow of liquid from the well until flowing of inlet pressure fluid through the valve.

4. A pressure fluid lifting apparatus disposed in the eduction tubing of a well, a movable inlet valve arranged in the tubing, an open ended cylinder flexibly connected to said valve, means providing inlet fluid communication between the valve and the cylinder, said cylinder responsive to the liquid level to provide a chamber maintaining inlet pressure fluid therein, said pressure fluid emitting from the valve into the chamber to effect a buoyancy to the cylinder whereby the valve is moved to flow pressure fluid therethrough into the eduction tubing at a point below the liquid level, and means for precluding the flow of liquid from the well until the flow of pressure fluid through the valve.

5. In a pressure fluid lifting apparatus disposed in the eduction tubing of a well, a valve collar, a movable inlet valve arranged therein, a complementary choke valve arranged above the inlet valve and simultaneously movable therewith, open ended means movable to sink and float in the liquid to be lifted, said means operably cooperating with the inlet valve whereby floating of the means will move the inlet valve to flow inlet fluid therethrough, and means for jetting the pressure fluid passing through the inlet valve in an upstream direction into the eduction tubing for displacing the liquid therefrom, said complementary valve precluding flow of liquid from the well until flowing of the pressure fluid through the inlet valve.

6. In an automatic intermitting system for lifting liquid from a well comprising an eduction tubing having a pressure lifting apparatus ar-

ranged therein, said apparatus adapted to allow expansion of pressure gas from the well to effect separation of the liquifiable constituents by condensation to provide a head of liquid in the well,

5 a valve collar arranged in the apparatus and having a movable inlet valve disposed therein, open ended means movable to sink and float in the condensates to be lifted, said means cooperating with the inlet valve whereby floating of the means will move the valve to allow passage of inlet pressure fluid therethrough into the eduction tubing for displacing the condensates.

7. In an automatic intermitting system for lifting liquid from a well comprising an eduction tubing having a pressure lifting apparatus arranged therein, said apparatus adapted to allow expansion of pressure gas from the well to effect separation of the liquifiable constituents by condensation to provide a head of liquid in the well,

15 a valve collar arranged in the apparatus and having a movable inlet valve disposed therein, open ended means movable to sink and float in the condensates to be lifted, said means cooperating with the inlet valve whereby floating of the means will move the valve to allow passage of inlet pressure fluid therethrough into the eduction tubing for displacing the condensates, and means precluding the flow of liquid from the well until the passage of inlet pressure fluid through the valve.

20 8. In a well pumping apparatus, a well bore, an eduction tubing string arranged in the bore for conducting liquid from the well to the top of the latter, means in the tubing string to obstruct the flow of liquid therethrough, a passage-way in said 35 means terminating in a choke, a valve controlling the passage of well fluid through said passage-way and choke, and a float in the tubing string arranged below said choke and operatively connected with the valve for controlling the latter.

25 9. In a well pumping apparatus, a well bore, an eduction tubing string arranged in the bore for conducting liquid from the well to the top of the latter, means in the tubing string to obstruct the flow of liquid therethrough, a passage-way in said 45 means terminating in a choke, a valve controlling the passage of well fluid through said passage-way and choke, a float in the tubing string arranged below said choke, and operatively connected with the valve for controlling the latter, and a loaded check valve arranged in the tubing string below the float for controlling the flow of liquid into the portion of the tubing string where the float is positioned.

30 10. In a well pumping apparatus, a well bore, an eduction tubing string arranged in the bore for conducting liquid from the well to the top of the latter, means in the tubing string to obstruct the flow of liquid therethrough, a passage-way in said 45 means terminating in a choke, a valve controlling the passage of well fluid through said passageway and choke, a float in the tubing string arranged below said choke and operatively connected with the valve for controlling the latter, and a bleed passage-way in the first mentioned means to allow gas to bleed upwardly through said means.

WALTER BRAUER.
